UNITED STATES PATENT OFFICE.

JAMES H. BLESSING, OF ALBANY, NEW YORK.

COMBINED CHECK AND STOP VALVE.

SPECIFICATION forming part of Letters Patent No. 300,837, dated June 24, 1884.

Application filed December 7, 1883. (No model.)

To all whom it may concern:

Be it known that I, JAMES H. BLESSING, of the city and county of Albany, in the State of New York, have invented certain new and 5 useful Improvements in Combined Check and Stop Valves, of which the following is a specification.

This invention consists in combining in one device a puppet check-valve and a straight-10 way screw stop-valve; and the object of my improvements is to provide a simple, effective, and inexpensive appliance as a substitute for the separate check-valve and screw stop-valve now commonly used in the feed-pipes 15 for steam-boilers. This object I attain by means of the construction illustrated in the accompanying drawings, which form part of this specification, and in which—

Figure 1 is a longitudinal section of a valve 20 containing my improvements; Fig. 2, a side elevation of the same; Fig. 3, a vertical section of the removable valve-seat for the check-valve, and Fig. 4 a side elevation of the same.

As represented in the drawings, A is the 25 valve-casing, having a globular valve-chamber, a, an inclined valve-chamber, a', induction-opening a'', and eduction-opening a''. A partition, B, like those commonly made in 30 globe-valves, is formed in the chamber a, and is provided with a circular opening, b, and an annular tongue, b', that is concentric to said opening.

C is a removable valve-seat, having an opening, c, that corresponds to the opening b in 35 the valve-casing, and an annular groove, c', that is adapted to fit over the annular tongue b' of said casing. An elastic packing, c'', is fitted into the annular groove c', for the purpose of forming a tight joint with the tongue b'. Openings c'', formed in the cylindrical portion of the removable valve-seat C, afford an egress for the escape of any liquids that 40 pass through the device. The removable valve-seat C and its mode of attachment to the partition B of the valve-casing constitutes a separate and independent invention, for 45 which Letters Patent of the United States

No. 272,634 were granted to me on the 20th day of February, 1883.

D is the check-valve of the device, made in a puppet form, and adapted to close over the opening c in the removable valve-seat C; or when the latter is omitted, (as it may be when preferred,) said valve can be arranged 55 to close over the opening b in the partition B, after the manner of the ordinary check-valve.

E is a cap for closing the opening in the upper side of the valve-chamber a, as shown 60 in the drawings. Said cap is adapted to bear upon the upper end of the removable valve-seat C, so as to secure the latter in place, as fully explained in my former Letters Patent hereinabove referred to.

F is an inclined partition formed across the eduction-opening a'' of the valve-casing. Said partition is arranged at right angles to the center line of the inclined valve-chamber a', adjacent to the check-valve D, and forms a 70 valve-seat for the stop-valve G, for which purpose it is provided with a circular opening, f, that is centrally located under the valve-chamber a', as shown in Fig. 1.

G is the stop-valve of the device. It is attached by means of a revoluble joint to the lower end of the screw-stem g, which, at its outer end, is provided with a hand-wheel, g', or other suitable appliance for operating the said stem.

H is the bonnet for the inclined valve-chamber a'. Said bonnet is provided on its outer end with the usual stuffing-box, h, for producing a tight joint around the stem g, and with an internally-screw-threaded portion, h', that serves as a nut for said screw-stem.

By arranging the partition F in an inclined position and placing it in close proximity to the check-valve D, the discharge of the liquid follows a direct line after it passes through the check-valve, and by this means only a single point of deflection from a straight line occurs while the liquid is passing through the device.

I claim as my invention—

95

A combined check and stop valve of the character described, when composed of a valve-casing, A, provided with the valve-chambers a and a' , a vertically-operating 5 check-valve, D, and an inclined screw stop-valve, G, the valve-chamber a being provided with a horizontal partition, B, and the valve-chamber a' being arranged in an inclined po-

sition and provided with a partition or seat, F, which is fixed at right angles to the central line of said valve-chamber, as herein specified.

JAMES H. BLESSING.
